Application July 1, 1952, Serial No. 296,562

5 Claims. (Cl. 34—187)

1

Our invention is an improvement in drying apparatus particularly a machine for drying sheets of any material, bearing photographic reproductions, printing in ink or other visible representations.

An important object of this invention is to provide a drying mechanism of relatively small size and large capacity, constructed so that it can be easily loaded and unloaded, and very efficient in operation.

Another object is to provide a drying machine containing heating units, such as electric lamps, and means for supporting the sheets to be dried so as to expose them to said units and dry them quickly, evenly and uniformly over their entire extent.

These and other objects and advantages are made apparent in the following detailed description and the novel characteristics are pointed out in the claims. The structure illustrated in the drawings represents the best form of the invention now known to us, but changes in various details and the shape and arrangement of the different parts of the machine may be made without really altering or deviating from the general design in which the invention is embodied.

On said drawings:

Figure 1 is a vertical section on lines 1—1 of Figures 2 and 3 of the entire drying apparatus.

Figure 2 is a rear view of the casing of a ventilator unit therefor.

Figure 3 is a top plan of the apparatus with ventilating unit removed.

Figure 4 is a front elevation of the machine without the ventilator unit; and

Figure 5 is a section on line 5—5 in Figure 4.

A frame work comprising uprights 1, upper horizontal beams 2 and lower horizontal beams 3, and generally square in horizontal cross section supports a round turntable 4 which is connected to be revolved by an electric motor 5 below the table. Just above the table are heating members such as electric lamps 6 mounted in fixed cross bars 7. The table is fixed to the upper end of a vertical shaft 8 mounted in a bearing 9 in the frame work and fixed on the shaft is a gear 10, driven by the motor 5 through reduction gearing 11. This gearing is coupled to the gear 9 by a shaft 12. Motor 5, bearing 9 and gear casing 11 are all mounted on a vertically movable base plate 14. The sheets to be dried are laid on the table 4 after being inserted through the open front of the framework between the table 4 and the heaters 6. The motor operates the reduction gearing through pulleys connected by a belt as indicated at 15.

2

The framework is open at the top and resting thereon is a ventilator unit comprising a casing 16 enclosing a fan blower 17 and deflector plates 18. The fan is at the rear of the casing and the baffle plates 18 are fixed inside the casing between the front and back in position to deflect the air impelled by the fan 17 down past the heaters 6 and directly upon the table 4 and the sheets it carries on its upper surface. The casing is flush with the front and sides of the framework but projects at the back. The fan rests on a supporting plate or base 19 and a transverse vertical web 20 in the casing 16 extends from the upper end of the frame work downward and forms with the back of the casing and adjacent portions of the sides an inlet flue 21 for air. Below the base 19 in the web is a transverse opening 22. Inside the casing are angle pieces 23 at the front which project and engage the horizontal bars 2 at the top of the framework and a cross bar 24 in the casing rests on the rear of the framework at the top to support the casing; and side bolts may be inserted in holes 25 to secure the casing to the rear uprights and hold the casing firmly in place.

The blower fan is driven by a motor 26, or by gearing if desired, and suitable electrical connections, not shown, are provided. The sheets to be dried are laid on the table 4 and arranged as required in one layer, with the table in uppermost position, and it rotates under the lamps till the drying is completed. Other sheets are then added and the table is lowered bit by bit till no more layers can be put on and at the end of the run all the sheets can be removed at once.

During the drying operation the fan blower 17 revolves and air is impelled past deflectors 18 and down on the sheets carried by the table 4. Some air warmed by the heaters 6 returns to the inlet flue 21 by way of the opening 22 in the web 20.

The up and down movement of the table 3 and base plate 14 is accomplished by means of cables 27 which lift and lower the table according to the operation of a horizontal rod 28 extending from front to rear of the framework at the top. This shaft is mounted in a bearing 29 at the front and a bearing 30 in back and on its front end outside of the framework is a crank disk 31. Between the bearings the shaft is threaded and passes through the threaded bore of a block 32 that has in its under face a groove receiving a key rod 33 fixed to the framework under the casing 15 to prevent the block from rotating. To this block the cables 27 are affixed. They pass

over pulleys 34 on vertical axes and guide pulleys 35 on horizontal axes, one at each corner of the framework, down to the level of the base plate 14 and are made fast at their lower ends. As the crank disk 31 is turned the rod 29 is rotated to move the block 32 to pull the cables 27 up and raise the table, or let them down to lower the table 3.

The base plate 14 for the motor 5, bearing 8, and reduction gear casing 11 rests on a square open lower frame 36. Above this frame is a similar frame 37, and the two frames consist of bars 38 united at the ends, and these frames are joined by vertical bars 39. The table 4 is over the upper frame 37. The cables 27 are made fast at their lower ends to the frame 36 in any suitable manner as by connecting the ends to diagonal pins 40 spanning the corners of the frame 37. The cables are included in Figures 2 and 3, but omitted from Figure 1, for convenience.

The uprights 1, and horizontal beams 2 and 3 are preferably angle bars suitably bevelled on both flanges at their ends, so as to be flush and make a neat fit, and said ends can be welded or otherwise fastened together. The bars 39 are also angle bars fitting the inside of the uprights 1. The upper frame 37 has a fixed cross bar 41 with a bearing 42 for the shaft 8. The table has a socket or hub 43 in its lower side in which the upper end of the shaft 8 is made fast.

The pulleys 34 are mounted on a cross bar 44 extending from side to side of the framework just below the upper beams 2. The ends 45 of this bar are bent up and welded or otherwise secured to the vertical flanges of the beams 2 at the sides of the framework. The bar 44 carries shouldered studs 46 on which the pulleys 34 are pivoted. The rear bearing 30 for the rod 28 is on the bar 44, and the front bearing 29 is secured to the inner face of the vertical flange of the beam 2 across the front of the framework.

The pulleys 35 are mounted on pivot studs in bearing plates 47 secured to the inner faces of the vertical flanges of the top horizontal beams 2. The pivot studs 48 project at the proper angles from the plates 47, so as to hold the pulleys 35 in required positions with respect to the pulleys 34. All the pulleys are grooved.

The key rod 33 is joined to the bottom of the bar 44 and to the front bearing 31 of the threaded cable rod 28. This rod 28 has pins 49 adjacent the bearings 30 and 31 to prevent longitudinal movement of the rod 28.

The framework has rollers or casters 50 at the lower ends of the upright 1, and may carry a switch 51 to control the circuit of the motors 5 and 26, and a counter 52 to indicate the number of revolutions of the table 4. The attendant allows the drying to continue during a predetermined number of revolutions of the table for each layer of sheets which he deposits thereon.

The construction shows the general combination of parts of the apparatus and the invention is not limited to the precise shape and relative positions of the parts as illustrated. The operating rod or member 28 and block 34 which move the cables need no stop, as the pull on the cables 27 is never sufficient to cause the block to move along the length of the rod 28.

Having described our invention, what we believe to be new is:

1. Drying apparatus comprising a horizontal table, means for supporting said table so that it can be raised and lowered, means for vertically adjusting said table and said supporting means,

means for revolving said table in all positions of adjustment, and heating means and a ventilator unit above said table, said supporting means comprising an upper frame and a lower frame in said framework, said revolving means including a motor and gearing connecting said motor to the table, the motor and gearing being mounted in one of said frames, and the table above the upper frame, said adjusting means comprising cables connected to one of said frames and an operating member for said cables.

2. Drying apparatus comprising a horizontal table, means for supporting said table so that it can be raised and lowered, means for vertically adjusting said table, means for revolving said table in all positions of adjustment, and heating means and a ventilator unit above said table, said supporting means comprising an upper frame and a lower frame in said framework, said revolving means including a motor and gearing connecting said motor to the table, the motor and gearing being mounted in one of said frames, and the table above the upper frame, said adjusting means comprising cables connected to one of said frames and an operating member for said cables, said unit comprising a casing resting on the top of the framework, an air impeller and deflector plates in the casing above the framework and an air inlet flue at the rear below the top of said framework.

3. Drying apparatus comprising a horizontal table, means for supporting said table so that it can be raised and lowered, means for vertically adjusting said table, means for revolving said table in all positions of adjustment, and heating means and a ventilator unit above said table, said supporting means comprising an upper frame and a lower frame in said framework, said revolving means including a motor and gearing connecting said motor to the table, the motor and gearing being mounted in one of said frames, and the table above the upper frame, said adjusting means comprising cables connected to one of said frames and an operating member for said cables, said unit comprising a casing resting on the top of the framework, an air impeller and deflector plates in the casing above the framework and an air inlet flue at the rear below the top of said framework, said flue having a return inlet adjacent said heating means.

4. Drying apparatus comprising an upright frame, a horizontal table therein, means in said framework for supporting said table so that it can be raised and lowered, means for vertically adjusting said table and said supporting means, the table being above said supporting means, means carried by the supporting means for revolving said table in all positions of adjustment, heating means and a ventilator unit mounted on the top of said framework, the ventilator unit comprising a casing extending downward below the top of the frame at the sides and rear, said casing having a transverse vertical web between its sides at the rear enclosing an air inlet flue with open lower end, said web having an opening above said end for return of air in said flue, said casing also containing an impeller fan at the rear in line with said inlet flue.

5. Drying apparatus comprising an upright frame, a horizontal table therein, means in said framework for supporting said table so that it can be raised and lowered, means for vertically adjusting said table and said supporting means, the table being above said supporting means, means carried by the supporting means for re-

volving said table in all positions of adjustment, heating means and a ventilator unit mounted on the top of said framework, said means for vertically adjusting the table and supporting means comprising cables attached to the supporting means, pulleys at the top of the framework over which said cables are passed, a block adjacent the top of the framework, a horizontal guide movably supporting said block and a threaded screw for imparting motion to said block to pull upon or release said cables to raise or lower the table and supporting means.
